(57) **CLAIM**

The ornamental design for a rail for a modular rack, as shown and described.

DESCRIPTION

FIG. 1 is a perspective view of a first embodiment of a rail for a modular rack showing our new design;

FIG. 2 is a front view thereof;

FIG. 3 is a rear view thereof;

FIG. 4 is a left side view thereof, the right side view being a mirror-image of FIG. 4;

FIG. 5 is a top plan view thereof, the bottom view being identical to FIG. 5;

FIG. 6 is a perspective view similar to FIG. 1, except that the rail is shown receiving a pair of slidable brackets, both being shown in phantom as environmental structure only and therefore forming no part of our claimed design; and,

FIG. 7 is a perspective view of a second embodiment of the rail for a modular bracket showing our new design, the front, rear, left side, right side, top and bottom views being similar to FIGS. 2-5, except for an extra pair of louvers.
